UNITED STATES PATENT OFFICE.

PETER HEATON, OF ALLEGHENY, PENNSYLVANIA.

DESIGN FOR A HOOK.

SPECIFICATION forming part of Design No. 28,724, dated May 31, 1898.

Application filed April 16, 1898. Serial No. 677,892. Term of patent 3½ years.

To all whom it may concern:

Be it known that I, PETER HEATON, a citizen of the United States of America, residing at Allegheny, in the county of Allegheny and State of Pennsylvania, have invented a certain new and useful Design for Hooks, of which the following is a specification, reference being had therein to the accompanying drawing.

10 My design of hook is particularly adapted for a picture-hook, and the drawing shows a perspective view of the same.

The leading or essential features of my design consist of the plate A, having an upwardly-extending portion B, practically diamond-shaped in its form, the two extending ears or side wings C, and the dependent strap D, which is bent upon itself in order to form the hook E. On the outer face of the plate, 15 adjacent to the rim thereof and continuing around the sections B and C, I provide a scroll or ornamentation F. I also provide the outer face of the hook E with a scroll or or-

namentation, which may be of diamond shape, arranged within a square or oblong scroll, as 25 shown at G. Centrally of the plate A and surrounding the aperture H are two practically diamond-shaped scrolls or ornamentations I, one arranged within the other, and a like design K is arranged around the central 30 aperture L in the upwardly-projecting portion B. Around the apertures M, that are formed centrally of the ears or side wings, I provide circumferentially-extending scrolls or ornamentations N.

35 Having described my invention, what I claim as new, and desire to secure by Letters Patent, is—

The design for a hook, as herein shown and described.

40 In testimony whereof I affix my signature in the presence of two witnesses.

PETER HEATON.
